ELECTRIC SWITCH

Stanley L. Frank, Beaver, Pa., assignor to Westinghouse Electric Corporation, East Pittsburgh, Pa., a corporation of Pennsylvania

Application September 9, 1947, Serial No. 772,938

12 Claims. (Cl. 200—18)

1 This invention relates generally to electric switches, and more particularly to such switches as are commonly employed in circuits for controlling electrical apparatus.

Electric switches of the type described generally take the form of pushbutton switches, or they may be of the rotary selector switch type. Each type of switch is often used in locations where a liquid, such as the oil used as lubricant or coolant for machine tools may be splashed against the switches, and one object of this invention is to provide a novel switch design of this type which is moisture-proof.

A more particular object of this invention is to provide a novel moisture-proof mounting for a switch operating member in a panel, with the switch contacts being mounted at the back of the panel.

Switches of the type described are used for a great variety of purposes wherein they are required to control in varied manner from one to a number of circuits. Instead of having a relatively large number of different switch designs for such various applications, another object of this invention is to provide a novel switch structure wherein the switch operating member and switch proper comprise novel, separate, interchangeable units.

Another object of this invention is to provide a novel basic switch unit which is capable of use with different types of switch operating units.

Still another object of this invention is to provide a novel switch unit having parts some of which are interchangeable, and all of which are adapted to be laid in appropriate recesses in a switch base and to be secured in operative position by such recesses and by a removable cover for the base.

A more specific object of this invention is to provide a novel attachment for a switch of the type described for locking the switch in a predetermined position.

Still another object of this invention is to provide a novel rotary locking means for a pushbutton type of switch.

A further object of this invention is to provide a novel switch operating unit separate from the actual switch unit including the switch contacts.

These and other objects of this invention will become more apparent upon consideration of the following detailed description of preferred embodiments thereof, when taken in connection with the attached drawings, in which:

Figure 1 is a side elevation view of a switch con-

structed in accordance with this invention with the operating unit thereof shown in section, and with the cover plate for the switch unit removed;

5 Fig. 2 is an end elevation view of a modified switch constructed in accordance with this invention, with the operating unit for the switch being shown in section;

10 Fig. 3 is a vertical section view of another modified form of switch constructed in accordance with this invention, with the section through the switch unit taken substantially at one set of contacts on the line III—III of Fig. 6, whereas the section through the switch operating unit extends substantially centrally thereof;

15 Fig. 4 is a transverse section view of the switch shown in Fig. 3, taken substantially on the line IV—IV thereof;

Fig. 5 is a developed view of the operating cam employed in the switch shown in Fig. 3;

20 Fig. 6 is a longitudinal section view taken through another modified form of switch constructed in accordance with this invention, with the section through the switch operating unit being taken substantially centrally thereof, and with the section through the switch unit being taken just inside the cover for the switch unit;

Fig. 7 is a bottom plan view of the operating cam employed in the embodiment of this invention shown in Fig. 6;

30 Fig. 8 is a top plan view of a switch like that shown in Fig. 1 with a locking arrangement secured thereto; and

Fig. 9 is an elevation view of the switch shown in Fig. 8 with the locking structure being shown in section taken substantially on the line IX—IX of Fig. 8.

35 Each of the switches disclosed herein comprises two unitary parts including an operating unit which has manually operable switch actuating means, and the switch unit proper which has the switch contacts. The operating unit and switch unit may be secured together in a number of different relations, and the arrangement is such that the switch units are adapted to be used with a number of different types of operating units. The switch units proper may be of either single or double arrangement as regards the number of poles, and preferably include contacts which may be interchanged and supported in a variety of different ways. The switch operating units all have provision for preventing the passage of moisture from the outer side to the inner side thereof, and further may include different types of pushbutton operating members or rotary selector operating members, or a combination of a pushbutton and

rotary operating member, and all of these different types of units have many parts in common.

The operating unit 2 illustrated in Figure 1 of the drawings is shown as being assembled with a switch unit 4 in a manner which will be hereinafter described. The operating unit 2 includes a tubular supporting sleeve 6, preferably of a cast metal, and having a flange 8 at the inner end thereof adapted to engage the inner side of a supporting panel 11. The panel 11 may be open at the rear, or enclosed in which case panel 11 forms the front wall of a switch box. Preferably, flange 8 of supporting sleeve 6 has a positioning pin 10 secured thereto which is adapted to be received in a recess provided at a predetermined position on the inner side of panel 11. A sealing disc 12 of any desirable moisture-proof compressible sealing material, such as rubber or the like, is interposed between flange 8 of the supporting sleeve and the inner surface of supporting panel 11. The outer end of supporting sleeve 6 is threaded for threadedly receiving a clamping ring 14 which is adapted to secure the sleeve to panel 11 when the clamping ring is drawn up tightly. If desired, a washer 16 having an extended portion at one side may be provided between clamping ring 14 and panel 11, and this washer may carry suitable indicia for proper identification of the switch, and for operative positions of the switch. Indicator washer 16 preferably is provided with key projections adapted to be received in external grooves 15 in sleeve 6 to properly position washer 16 on the sleeve and prevent relative angular movement.

Supporting sleeve 6 of the switch operating unit is interiorly provided intermediate its ends with a transversely extending web 18 which is centrally apertured for slidably receiving an operating rod 20. A pushbutton 22, preferably of a molded insulating material, is illustrated as being secured to the outer end of operating rod 20, preferably by being molded thereon. Pushbutton 22 is provided with an annular skirt 23 which is engageable with the outer surface of web 18 to determine the extent of inward movement of pushbutton 22. A coil compression spring 24 is interposed between pushbutton 22 and a retainer disc 26 seated on web 18, to normally bias the pushbutton to the outer limit of its movement. The part of retainer disc 26 which seats on web 18 is adapted to engage a sealing disc 28, also of a moisture-proof resilient material such as rubber, for sealing any space between operating rod 20 and the opening through web 18. The portion of retainer disc 26 which is engaged by spring 24 is offset into an annular drain recess 34 provided in web 18, and this recess communicates with the exterior of supporting sleeve 6 by means of a plurality of radially extending drain openings 36 (only one of which is shown). In order to permit drainage of liquid through drain openings 36, clamping ring 14 is provided with a plurality of notches 38 in the inner edge thereof, and it will be observed that the extreme inner end of clamping ring 14 is not threaded, but is actually spaced from the outer surface of supporting sleeve 6 to form a drain channel 39 therebetween, so that it is not necessary that a notch 38 be lined up opposite each drain opening 36.

The operating unit 2 described above is thus adapted to be secured to a supporting panel 11 or the like, in a manner to prevent the passage of moisture from one side of the panel to the

other, and it embodies a pushbutton 22 normally biased to an outer position defined by an operating disc 30 secured on the reduced inner end of operating rod 20, as by riveting over the outer end of the rod as at 32. The opening through which the operating rod moves is also sealed against the passage of moisture from the front to the rear, and any moisture which may accumulate within operating sleeve 6, particularly when the latter is mounted in a vertical position such as that shown in Figure 1, will drain from the interior of the sleeve through the drain passages provided, irrespective of the relative angular position of clamping ring 14 and sleeve 6.

The switch unit 4 which is employed with operating unit 2 in Figure 1 is similar to the units 106, 162 and 179 shown in Figures 2, 3 and 6, and accordingly, many of the parts being identical, the same reference numerals have been used throughout to designate such like parts. Therefore, for a better understanding of the construction of these switch units, reference may be had to all of these figures. Switch unit 4 includes a base 40 of insulating material, preferably a molded insulating material. Switch base 40 is provided with opposed recessed projections 41 and 43 at one side thereof, and has on the same side another pair of opposed projections 42. All of the projections 41, 42 and 43 are spaced apart so as to provide in effect a recessed space 44 between the inner ends of the several projections. Projection 41 has a recess 46 extending throughout the length of the projection and having an outer reduced portion forming an internal shoulder, and projection 43 has a recess 47, the outer end of which is closed. Projections 42 are spaced from opposite sides of projections 41 and 43 to form spaces 48 therebetween. Spaced contact receiving slots 52 are provided at the inner side of each projection 42 for receiving one edge of a straight contact member 54, with the opposite edge being received in a recess provided in the adjacent corner of projection 41. The inner end of each contact 54 is provided at the side adjacent projections 41 and 43, with an extension 56 adapted to be seated in a slot 50 provided in space 48 to thereby hold the contact against lateral movement relative to the base in cooperation with slot 52. Each contact 54 is provided with a shoulder 58 positioned to be engaged by a cover 68 when secured to base 40, to prevent withdrawal of the contact from slots 50 and 52. Each contact strip 54 is provided with a contact button 60 adapted to be positioned within space 48. As illustrated in Figures 1 and 2, straight contact strips 54 are secured in the lower set of slots 50 and 52 in each space 48 on base 40, and generally U-shaped contact strips 62 are mounted in the upper slots 52. The U-shaped contacts 62 each have one leg carrying a contact button 64 which is adapted to have one side received in a slot 52, with the other side thereof resting in the recess provided in the adjacent corner of projection 41. The bight portion of each contact 62 is adapted to engage base 40, with the other leg of each contact strip 62 extending beyond projections 42 and resting against an adjacent flange 70 integral with each projection 42. Such other leg of each contact strip 62, as well as the outer ends of contact strips 54, are provided with terminal screws 66 for the purpose of securing conductors thereto. It is apparent that contact strips 62 are maintained against withdrawal from slots 52 by engagement of cover 68 with the leg of these con-

tact strips which carry contact buttons 64. Preferably, cover 68 is secured in position by any desired means, such as bolts or the like, engaged in openings 67 provided in opposite sides of the base 40 of the switch unit.

The switch unit further includes an operating member 72 of insulating material, preferably a molded insulating material, adapted to be received in the recess 46 of base projection 41, and having a reduced operating extension 74 extending through the reduced recess opening at the outer end of projection 41, to provide a shoulder 76 around three sides of operating member 72 which is engageable with the shoulder adjacent the outer end of recess 46 to limit the extent of outward movement of the operating member. A contact supporting strip 75 is secured to the inner end of operating member 72, preferably by being cemented therein, and it is adapted to have a bridging contact bar 78 slidably mounted thereon. Bridging contact bar 78 is provided with contact buttons 80 on opposite sides thereof at each end of the bar, for cooperation with the respective contact buttons of contact strips 54 and 62. Contact supporting strip 75 has a reduced extension 82 on which is slipped a spring supporting sleeve 84, also preferably of an insulating material. A coil compression spring 86 is adapted to be received in recess 41 of base projection 43, and to react between the closed end of this recess and sleeve 84 to normally bias operating member 72 to its outermost position, where the contact buttons of bridging contact bar 78 engage the upper contacts 64 mounted on the base. It will be observed that the upper end of spring supporting sleeve 84 is provided with a transverse notch 88 for receiving the lower end of contact supporting strip 75 to space bridging contact bar 78 upwardly a predetermined distance. A coil compression spring 87 which is weak relative to spring 86 is provided on contact supporting strip 75 and reacts between operating member 72 and the contact bridging bar. Preferably, a notch 89 extends across the space between opposed pairs of contacts for the purpose of increasing the creepage distance between each pair of contacts.

It will be observed that the switch unit is pre-formed to have the various projections, recesses and notches described, so that all of the switch contacts and operating parts may be assembled with the base merely by laying them in their appropriate recesses or slots. Thus contacts 54 and 62 can be merely laid into notches 52, and the entire movable contact assembly comprises parts which are unsecured together, being merely mounted in telescoping relation and held assembled by biasing spring 86. Moreover, the contacts including the movable contact bridging bar and operating elements therefor are all held against removal from base 40, and against movement from their operative positions relative to the base merely by cover 68.

It will be apparent that the operating member 72 for the switch unit may be depressed by exerting pressure on the outer end of operating extension 74 to be moved from the position illustrated on the drawings wherein the contact buttons of bridging bar 78 engage the upper set of stationary contact strips, to a position where they engage the lower set of stationary contact strips, and extension 74 may be moved beyond this position due to the slidable mounting of the bridging contact bar on contact supporting strip 75.

75, with such movement acting to compress spring 87 as well as spring 86. As soon as operating extension 74 is released, spring 86 will return the parts to the position illustrated in the drawings wherein bridging contact bar 78 has its contacts in engagement with the upper set of stationary contacts on base 40.

The switch and operating units are preferably assembled in operative relation by screws 90 extending through openings provided at opposite ends of base 40 of switch unit 4. The switch unit may be positioned so that screws 90 may engage in either pair of opposed pairs of threaded sockets 91 provided in the flange 8 of operating unit sleeve 6, as may be convenient. It is immaterial insofar as the operating unit is concerned at what angular position the switch unit is secured thereto, because at any position operating disc 30 of the operating unit will engage operating extension 74 of the switch unit to depress the latter when pushbutton 22 is depressed, and thereby operate the contacts of the switch unit.

The switch shown in Figure 2 of the drawings 25 is similar in many respects to that shown in Figure 1, having many identical parts, and accordingly, these parts have been given the same reference numerals. The operating unit 92 employs a supporting sleeve 6 which is identical with 30 that previously described in connection with the embodiment of invention shown in Figure 1, the only difference in this operating unit being that incurred by use of a pushbutton 98 of the mushroom type, so called because it has a relatively large outwardly extending flange 100. Since flange 100 of the pushbutton prevents the unit from being assembled with panel 11 by insertion through the opening in the panel with the button in place, as in the case of operating 40 unit 2 shown in Fig. 1, it is necessary that button 98 be removable; and further to permit assembly of the unit with the button removed, an additional retainer disc 94 is provided for the upper end of spring 24, with the disc being held 45 on operating rod 20 by a pin 96 extending transversely through the rod above retainer disc 94. Pushbutton 98 is provided with a transverse threaded opening for receiving a setscrew 102 adapted to engage an annular groove 104 provided adjacent the upper end of operating rod 20.

In operation the unit 92 functions in a manner similar to unit 2 as described above, in that depression of pushbutton 98 is accomplished 55 manually and spring 24 acts to return the pushbutton to the position shown in Fig. 2. Moreover, spring 24, in addition to biasing the pushbutton to its normal projected position, also maintains sealing disc 28 under pressure to effectively seal the opening in web 18 through which the operating rod moves. In assembling operating unit 92 with panel 11, pushbutton 98 must be removed and reapplied after the unit has been inserted through the opening in the panel. 60 Obviously with pushbutton 98 removed, retainer disc 94 acts to retain spring 24 in unitary assembled relation.

The switch unit 106 shown in Figure 2 is a double unit in that the base is provided with contact strips 54 and 62 in recesses at opposite sides, with a movable contact assembly for each actuated by separate operating extensions 74, respectively. Upon depression of pushbutton 98, operating disc 30 will engage the respective operating extensions 74 at opposite sides to simulta-

neously actuate both movable contacts of switch unit 106.

The switch shown in Fig. 3 is of the rotary selector type having an operating unit 108 which is similar in some respects to the operating units previously described. Operating unit 108, however, has a supporting sleeve 110 having a flange 112 at one end thereof provided with a positioning pin 114 for cooperation with an aperture in panel 11 similar to supporting sleeve 6 shown in Figs. 1 and 2. Supporting sleeve 110 also has a sealing disc 116 provided between its flange 112 and panel 11 and held in compressed condition by a clamping ring 118 engaging the other side of the panel, with a washer 120 interposed therebetween. Clamping ring 118 is threaded on the outer end of supporting sleeve 110 so as to secure the supporting sleeve rigidly with respect to the panel.

Supporting sleeve 110 is provided with a transverse web 122 interiorly thereof intermediate the ends of the sleeve, and this web is centrally apertured for receiving a rotatable operating shaft 124. The operating shaft has a reduced inner end 126 of irregular shape so as to be non-rotatably received in a similarly shaped opening provided in an operating cam 128, which is secured thereto by a screw 130 extending through a central aperture in the cam and threaded into the inner end of operating shaft 124. A rotatable operating handle 131 is adapted to be molded on the outer end of operating shaft 124, and this handle is provided with an integral skirt flange 132, which extends into proximity with abutments 138 and 148 integral with web 122. At one side skirt flange 132 of the operating handle has an integral extension 134 adapted to engage opposite edges 136 of the substantially semi-circular abutment 138 integral with supporting sleeve 110 as well as web 122, to limit rotative movement of the handle and shaft 124. Abutment 138 is provided intermediate its ends with a bore 140 adapted to receive a coil compression spring 142 for biasing a ball detent 144 into engagement with the lower edge of handle skirt 132. Spaced notches 146 are formed in the lower edge of handle skirt 132 for cooperation with ball detent 144 to define various positions of the operating handle. Preferably, there are three such notches 146 for defining two operative positions of the handle, and an intermediate neutral position. The circular segmental abutment 148 in supporting sleeve 110 has the ends thereof spaced from the ends 136 of abutment 138, for a purpose which will appear in connection with the description of the embodiment of invention shown in Fig. 6.

Supporting sleeve 110 has an annular drain recess 150 with outwardly extending radial drain openings 153 for draining the interior of the supporting sleeve, and clamping sleeve 118 is notched as at 151 with the notched portions spaced from the outer surface of supporting sleeve 110 very much in the same manner as the supporting and clamping sleeves previously described in connection with the embodiments of invention shown in Figs. 1 and 2. Operating cam 128 is shown in developed form in Fig. 5 of the drawings as including a high point surface 152 connected with an intermediate surface 154 by sloping surfaces 156, and these, in turn, are connected with a low point surface 158 by sloping surfaces 160, for a purpose to be described.

The switch unit 162 shown in Fig. 3 is similar to the switch units previously described having

identical parts which are identified by the same reference numerals, and accordingly, description of such parts will not be repeated. The only difference in switch unit 162 is that the straight contacts 54 and U-shaped contacts 62 have been interchanged from the positions shown in Figs. 1 and 2, in that the former are adjacent operating member 72 rather than remote therefrom as shown in Figs. 1 and 2, and the U-shaped contact members are remote from the operating member.

It will be apparent that with switch unit 162 assembled with operating unit 108, as shown in Fig. 3, operating extension 74 of the switch unit is in engagement with low point surface 158 of operating cam 128 of the operating unit. Upon rotation of operating handle 131 in a counter-clockwise direction, operating extension 74 of the switch unit will be forced down by engagement with a sloping surface 160 and eventually seat on intermediate point surface 154 where the contacts of bridging contact bar 78 will be at a position intermediate the contacts 64 of contact strips 54 and 62. Upon continued rotation of the operating handle in the same direction, operating extension 74 will be forced downwardly a further amount by a sloping surface 156 of the cam onto high point surface 152 wherein the contacts of bridging contact bar 78 will engage the contacts 64 of the contact strips 62. Obviously rotation of operating handle 131 in a reverse direction back to the position shown in Fig. 3, will cause the contacts to be operated in a reverse manner back to the position shown in this figure. Ball detent 144 in cooperation with notches 146 operates to define and hold the operating handle at each of the three positions described.

The switch shown in Figure 6 of the drawings embodies an operating unit 164 which has a combined push-button and rotary selector operating member. This unit employs a supporting sleeve which is identical with that shown in Fig. 3, and accordingly, a detailed description of this sleeve and its mode of support on panel 11 will not be repeated. The operating button 166 has a relatively short integral skirt 168 and normally is held at a position spaced from the abutments 138 and 148 within the supporting sleeve by spring 24. However, skirt 168 of the operating button has an integral projection 170 for defining certain rotative positions of the operating button, and for guiding the button in its sliding movement. An operating cam 172 is secured to the inner end of operating rod 124, and has a high point surface 174 with a shoulder 175 at each end adjoining sloping surfaces 176 at each side thereof which terminates at an open side 178 of the cam.

Operating unit 164 may be assembled with the switch unit 179 which is identical in most respects with the unit shown in Fig. 2, being of the double type like the unit of Fig. 2, but with the contacts 54 and 62 positioned like those in Fig. 3, that is, with straight contacts 54 adjacent operating member 72 and U-shaped contact strips 62 remote therefrom. With operating unit 164 and switch unit 179 assembled as shown in Fig. 6, it will be apparent that one operating extension 74 of the switch unit is positioned in the open side 178 of the operating cam when operating handle extension 170 is in engagement with one end 136 of circular abutment 138 within supporting sleeve 110. At the same time the opposite operating extension 74 of switch unit 179 will be in engagement with the high point surface 174 of the op-

erating cam which will maintain the movable contact of that extension intermediate that of its fixed contacts. Since projection 170 of the operating handle is then at a position between the ends of supporting sleeve abutments 138 and 148, the handle may be depressed to move the switch operating extension 74 in engagement with high point surface 174 of the operating cam to a position where the contacts of its bridging contact bar engage the contacts 64 of contact strips 62, without moving the operating extension 74 which is located at the open side 178 of the operating cam. Of course, when handle 166 is depressed, it cannot be rotated because projection 170 is then located directly between adjacent ends of supporting sleeve abutments 138 and 148. When the handle is released and returned to the position shown in Fig. 6 by its biasing spring 24, it is prevented from unintentional rotation by shoulders 175. However, when the handle is at its extended position, it may then be manually rotated, since handle projection 170 will then be located in a plane above supporting sleeve abutment 148. Rotation may occur only in a counterclockwise direction from the position shown in Fig. 6 because the lower end of projection 170 is not above the upper surface of circular abutment 138 of the supporting sleeve. In thus rotating operating handle 166, a sloping surface 176 of the operating cam will force the operating extension 74 located at the open side 178 of the cam downwardly while the other operating extension 74 will be forced over a shoulder 175 and onto the other sloping surface 176 which will permit the operating extension 74 which had been in engagement with the high point surface 174 of the cam to be moved upwardly by its biasing spring 86 to its fully extended position. Projection 170 of operating handle 166 will finally engage the other end 138 of abutment 138 of the supporting sleeve at a position about 180° from that shown in Fig. 6, where the operating member may be again depressed for operation solely of the operating extension 74 which was unaffected when the button was depressed in the position shown in Fig. 6. It is believed apparent that the combined pushbutton and selector switch shown in Fig. 6 may take the place of two separate buttons employed in the control of motors where it is desired to manually "inch" the motor. For this purpose one part of the double switch unit 179 being capable of performing this "inching" function upon depression of operating handle 166 when at one extreme of its rotative movement, with the other set of contacts of the switch unit being used to start the motor by depression of the operating member when at the other extreme of its rotative movement.

It is often desirable, particularly with pushbutton switches of the type shown in Fig. 1, to have provision for locking the pushbutton member at a depressed position. One means of accomplishing this with an operating unit 2 of the type shown in Fig. 1 is illustrated in Figs. 8 and 9 as an attachment for such an operating unit. This locking attachment comprises a mounting ring 181 adapted to be secured on the outer end of supporting sleeve 6, as by setscrews 133 at one side of the mounting ring. An integral extension 185 is provided at one side of mounting ring 181 with an aperture 187, for a purpose to be described. A locking ring 180 is provided with inwardly extending pins 182 adapted to be received in inclined grooves 184 provided in opposite sides of mounting ring 181, when the locking ring 75

is telescoped over the mounting ring. Locking ring 180 is provided with an inwardly extending flange 188 at one side adapted to be received in an inclined cutout portion 189 of the mounting ring, and with an opposed longer flange 186 adapted to extend over a similarly cutout portion 191 in the upper edge of mounting sleeve 181. Flange 186 is adapted to extend over pushbutton 22 for a purpose to be described. Locking ring 180 is provided with a bore 193 opening beneath flange 186 for receiving a coil compression spring 192 which urges a ball detent 194 downwardly into engagement with the upper surface of mounting ring 181. Locking ring 180 is provided with integral extension 196 which is apertured as at 197 similar to the extension 185 of mounting ring 181.

It will be apparent that locking ring 180 may be rotated relative to mounting ring 181 by grasping extension 196 thereof and moving it to the extent permitted by slots 184 in which pins 182 are received. The parts are illustrated in Figs. 8 and 9 at the innermost position of locking ring 180 where its pins 182 are received in the innermost ends of grooves 184 of mounting ring 181. At this point ball detent 194 is received in a recess 198 for defining the locking position of ring 180 wherein flange 186 holds pushbutton 22 at a depressed position, for example, a position wherein the contacts of bridging contact bar 78 are intermediate the fixed contacts of the associated switch unit. At this position of locking ring 180, the opening 197 in its extension 196 is aligned with the opening 197 in the extension 185 of mounting ring 181, so that a padlock or similar locking member may be inserted through both openings to lock the pushbutton at this position. Upon rotation of locking ring 180 counterclockwise from the position shown in Fig. 8, it will be apparent that its pins 182 riding in slots 184 will cause the locking ring to move outwardly relative to mounting ring 181 during such rotative movement so that when its extension 196 is at the dotted line position shown in Fig. 8, its flange 186 will no longer maintain pushbutton 22 depressed, and the ring will remain at this position due to engagement of ball detent 194 with a second depression 200 in the upper edge of mounting ring 181.

The pushbutton locking arrangement described above is particularly described and claimed in my copending application Serial No. 362,723, filed June 19, 1953 on Electric Switches and assigned to the same assignee of this invention.

In the various embodiments of the invention described above, it will be apparent that the invention comprises novel forms of switches, each of which comprises separate operating and switch units which may be assembled in a plurality of different relations. The operating units include reciprocable or rotary operating members, and one unit has an operating member which is capable of both reciprocable and rotative movement all for the purpose described. These operating units are similar in structure as to their supporting sleeves and as to the provision for preventing the passage of moisture therethrough, as well as to the means for draining accumulated liquid. As a matter of fact, of the four different types of operating units disclosed herein, there are only two different supporting sleeves. As regards the switch units, except for the differences between a single and double unit, these all are identical except as they illustrate the interchangeability of the stationary contacts.

The switch units are all illustrated as embodying straight contact strips 54 for one set of contacts and U-shaped contact strips 62 for the other set of contacts, with straight contacts 54 comprising the upper set of contacts in Figs. 3 and 6 so that the terminal screws 66 face downwardly for the purpose of making wire connections from the rear of panel 11, and with the positions of the contact strips 54 and 62 reversed in Figs. 1 and 2 to enable wire connections to be made from the front. These units may also employ U-shaped contact strips 62 for both sets of contacts or might employ straight contact strips 54 for both sets of contacts except that the latter arrangement would bring the terminals 66 very close together and would be objectionable because of this small clearance factor and, therefore, would be employed only for extremely low voltages unless additional insulation is provided. It is believed also apparent that any of the operating units disclosed may be employed with any of the switch units depending upon the circuits to be controlled and the functions desired in connection with that particular circuit.

Having described preferred embodiments of this invention in accordance with the patent statutes, it is desired that the invention be not limited to these particular devices inasmuch as it will be apparent that many changes and modifications may be made therein without departing from the broad spirit and scope of this invention. Accordingly, it is desired that the invention be interpreted as broadly as possible and that it be limited only as required by the prior art.

I claim as my invention:

1. Switch structure adapted to be mounted in an opening through a support, comprising, an operating unit including a sleeve member adapted to extend through said support opening and having means for securing said sleeve in said opening, a switch operating rod mounted for rotative and reciprocating movement in said sleeve and extending substantially centrally therethrough, manually operable means secured to the outer end of said rod, an actuating cam disc on the inner end of said rod, resilient means reacting between said sleeve and rod for normally biasing said rod to an outer position; cooperating stop means rigidly mounted on said sleeve member and manually operable means for limiting rotation of the latter, and for permitting reciprocation of said manually operable means only at selected rotative positions thereof; a switch unit comprising, a base having stationary contacts and at least one movable contact mounted on a reciprocally movable contact carrying member which has an actuating part projecting from one side of said base at a position offset from the center of the base; and means for securing said switch unit to the inner end of said operating unit with said contact carrying member part at either side of the center so as to be actuated by said actuating disc in response to movement of said operating rod.

2. Switch structure adapted to be mounted in an opening through a support, comprising, an operating unit including a sleeve member adapted to extend through said support opening and having a flange at one end adapted to engage the inner side of said support, a clamping ring threaded on said sleeve member to engage the outer side of said support when drawn tight to secure said sleeve member in said opening, a movable operating rod extending longitudinally

of said sleeve member, an enlarged operating member permanently secured to the inner end of said rod, switch means mounted at the inner end of said sleeve member for operation by said operating member, resilient means in said sleeve reacting between said sleeve and an abutment on said shaft, an enlarged operating head removably secured on the outer end of said rod, and cooperating stop means on said sleeve member and operating head for limiting both rotative and longitudinal movements of the latter.

3. Control switch structure comprising, stationary contact means, reciprocable contact means movable into and out of engagement with said stationary contact means, a rotary contact operating shaft having one end extending into proximity with said reciprocable means and having cam means thereon for causing reciprocation of said reciprocable means upon rotation of said shaft, a manually operable knob on the other end of said shaft, said knob having an integral inwardly extending skirt and detent means for determining various contact positions by cooperation with appropriately spaced notches in the inner edge of the skirt of said knob.

4. A switch unit, comprising, a base of insulating material having recesses at one side thereof, certain of said recesses comprising slots extending into said base from said one side to slidably receive stationary contact strips, another of said recesses extending substantially transversely of said first-mentioned recesses and opening at an edge of said base adjacent said one side for slidably receiving a movable contact-carrying member, said member and recess having cooperating shoulders limiting outward movement of the member, movable contact means slidably but non-rotatably telescoped onto said member for limited sliding movement relative thereto defined by an outer shoulder on said member and by resilient means having shoulder means acting on said member inwardly of said movable contact means for biasing said member toward the open end of said other recess, means biasing said movable contact means to the inner limit of its movement relative to said member, said resilient means comprising the sole means for holding said contact means on said member, and a cover removably secured to said one side of said base for holding all of the aforesaid parts mounted in said recesses in place.

5. A switch unit, comprising, a base of insulating material having recesses at one side thereof, certain of said recesses comprising slots extending into said base from said one side to slidably receive stationary contact strips, another of said recesses extending substantially transversely of said first-mentioned recesses and opening at an edge of said base adjacent said one side for slidably receiving a movable contact carrying member, contact means carried by said member, there being at least two of said recess slots spaced along said other recess, one of said contact strips being flat and having a terminal portion of reduced width extending from said one side of said base, the contact strip in the other recess slot having a terminal portion extending angularly away from said first contact strip to the outside of said base, said recess slots being substantially identical so that said two types of contact strips may be mounted in either, and a cover removably secured to said one side of said base for holding all of the aforesaid parts mounted in said recesses in place.

75. 6. Switch structure comprising, tubular sup-

porting means, a switch mounted at one end of said supporting means and having reciprocable contact means movable into and out of engagement with stationary contact means, an operating shaft movably mounted in said supporting means and having one end extending into proximity with said reciprocable means and having means thereon to cause reciprocation of said reciprocable means upon movement of said shaft, a handle on the other end of said shaft having an inwardly extending skirt, an inwardly extending stop projection on said handle skirt, an arcuate abutment in said supporting means having its ends positioned to be engaged by said projection for limiting rotative movement of said handle, and cooperating detent means on the inner end of said handle skirt and said abutment located at a point at the outer surface of said abutment intermediate the ends thereof.

7. Switch structure comprising, tubular supporting means, a switch mounted at one end of said supporting means and having reciprocable contact means movable into and out of engagement with stationary contact means, an operating shaft movably mounted in said supporting means and having one end extending into proximity with said reciprocable means and having means thereon to cause reciprocation of said reciprocable means upon movement of said shaft, a handle on the other end of said shaft, an inwardly extending stop projection on said handle, annularly spaced stop abutments in said supporting means for limiting rotative movement of said handle, an arcuate abutment in said supporting means intermediate said spaced abutments for preventing sliding movement of said handle and shaft inwardly, and at least one end of said arcuate abutment being spaced from the adjacent one of said spaced abutments a distance to accommodate said stop projection to permit inward sliding movement of said handle and shaft at one rotative position thereof while preventing rotation thereof when moved inwardly.

8. Switch structure comprising, a supporting sleeve member adapted to be mounted in an opening provided in a supporting plate member, an operating member movably mounted in said sleeve member and having an operating handle on its outer end and a switch operating member at its inner end, a switch base of insulating material having a plurality of mounting holes therethrough so that it may be mounted in proximity to said switch operating member on said plate member or on a support at the opposite side thereof, said base having recesses at one side thereof, certain of said recesses comprising slots extending into said base from said one side to slidably receive stationary contact strips, another of said recesses extending substantially transversely of said first-mentioned recesses and opening at an edge of said base adjacent said one side for slidably receiving a movable contact carrying member, contact means carried by said member, there being at least two of said recess slots spaced along said other recess, one of said contact strips being flat and having a terminal portion of reduced width extending from said one side of said base, the contact strip in the other recess slot having a terminal portion extending angularly away from said first contact strip to the outside of said base, said recess slots being substantially identical so that said two types of contact strips may be mounted in either, and a cover removably secured to said one side of said base for holding

all of the aforesaid parts mounted in said recesses in place.

9. Switch structure comprising, tubular supporting means, a switch mounted at one end of said supporting means and having reciprocable contact means movable into and out of engagement with stationary contact means, an operating shaft movably mounted in said supporting means and having one end extending into proximity with said reciprocable means and having means thereon to cause reciprocation of said reciprocable means upon movement of said shaft, a handle on the other end of said shaft, an inwardly extending stop projection on said handle, annularly spaced stop abutments in said supporting means for limiting rotative movement of said handle, an arcuate abutment in said supporting means intermediate said spaced abutments for preventing sliding movement of said handle and shaft inwardly, and opposite ends of said arcuate abutments being spaced from said spaced abutments, respectively, a distance to accommodate said stop projection to permit inward sliding movement of said handle and shaft at two spaced rotative positions thereof while preventing rotation thereof during such inward movement.

10. Switch structure comprising, tubular supporting means, a switch mounted at one end of said supporting means and having reciprocable contact means movable into and out of engagement with stationary contact means, an operating shaft movably mounted in said supporting means and having one end extending into proximity with said reciprocable means and having means thereon to cause reciprocation of said reciprocable means upon movement of said shaft, a handle on the other end of said shaft, an inwardly extending stop projection on said handle, annularly spaced stop abutments in said supporting means for preventing sliding movement of said handle and shaft inwardly, and at least one end of said arcuate abutment being spaced from the adjacent one of said spaced abutments a distance to accommodate said stop projection to permit inward sliding movement of said handle and shaft at one rotative position thereof while preventing rotation thereof when moved inwardly.

11. Control switch structure, comprising, stationary contact means, reciprocable contact means movable into and out of engagement with said stationary contact means, comprising spaced reciprocable contact carrying members, actuating means for said members comprising an actuating rod mounted for rotary and longitudinal sliding movement in a direction paralleling the direction of reciprocable movement of said members, fixed stop means limiting outward movement of said rod, an operating member secured to the outer end of said rod for both rotating and reciprocating the rod, an operating member carried by said rod and located at one side only adjacent said members so as to be capable of engaging only one of said members at a time, said members being biased to extended positions adjacent said operating member, and said rod being biased to an extended position away from said members, whereby said rod may be angularly adjusted while at its aforesaid extended position to select

either one of said members to be actuated upon reciprocal movement of said rod while the other member is unaffected by such reciprocal movement, and cooperating stop means on said rod and a stationary support, respectively, including angularly spaced stop members for limiting rotative movement of said rod, and said respective stop means having longitudinally extending slidably engageable surfaces at the limiting positions to limit rotative movement of the rod during reciprocation thereof.

12. Control switch structure comprising two sets of spaced stationary contact means, a reciprocal contact carrying member for each of said sets of contact means movable into and out of engagement with the contact means of its respective set of contact means, actuating means for said members comprising an actuating rod mounted for rotary and longitudinal sliding movement in a direction paralleling the direction of reciprocal movement of said members, fixed stop means limiting outward movement of said rod, an operating member secured to the outer end of said rod for both rotating and reciprocating the rod, cylindrical cam means carried by said rod facing said members, said members being biased toward said cam means, and said cam means having a recess at one side so that at one angular position of said rod the member opposite the recess of said cam means is moved to the extreme of its movement under the influence of its bias while the other member is held at a position intermediate the stationary contact means of its set of contact means by direct engagement with said cam means and can be actuated into engagement with one of its associated stationary contact means by reciprocal movement of said rod, while at another angular position of said rod said other member will be positioned opposite the recess of said cam means and moved to the ex-

treme of its movement under the influence of its bias and the first mentioned member will be held at a position intermediate the stationary contact means of its set of contact means by direct engagement with said cam means and can be actuated into engagement with one of its associated stationary contact means by reciprocal movement of said rod, and cooperating stop means on said rod and a stationary support, respectively, including angularly spaced stop members for limiting rotative movement of said rod, and said respective stop means having longitudinally extending slidably engageable surfaces at the limiting positions to limit rotative movement of the rod during reciprocation thereof.

STANLEY L. FRANK.
